UNITED STATES PATENT OFFICE

151,782

DESIGN FOR A HANDBAG

Carolyn N. Munn, New York, N. Y.

Application July 3, 1947, Serial No. 140,081

Term of patent 14 years

(Cl. D87—3)

To all whom it may concern:

Be it known that I, Carolyn N. Munn, a citizen of the United States of America and a resident of New York city, county and State of New York, have invented the new, original, and ornamental Design for a Handbag, of which the following is a specification, reference being had to the accompanying drawing, forming part thereof, in which—

Fig. 1 is a front view of a handbag, embodying my design;

Fig. 2 is a side view thereof;

Fig. 3 is a top view thereof; and

Fig. 4 is a vertical section therethrough on a plane which extends from front to back, parallel to the sides.

Fig. 5 is a rear view of the handbag, on a reduced scale:

I claim:

The ornamental design for a handbag, substantially as shown.

CAROLYN N. MUNN.
